UNITED STATES PATENT OFFICE

FRANK BAUMAN, OF HONESDALE, PENNSYLVANIA

SPINDLE

Application filed November 15, 1928. Serial No. 319,568.

The invention relates to spindles for silk quilling machines, and provides an article, which admits of ready replacement of worn journals without the substitution of entirely new spindles and incurring the expense incident to such substitution.

In accordance with the present invention the journals, when worn, may be easily detached from the spindle and readily replaced at a nominal cost compared with that experienced when the used spindle is scrapped and replaced by a new one.

The invention therefore consists of a spindle provided with replaceable journals, and the specific means desired whereby the journals may be removed and new journals substituted with the greatest facility.

While the drawing illustrates a preferred embodiment of the invention, it is to be understood that in adapting the means to meet specific needs and requirements, the design may be varied and such other changes in the minor details of construction may be resorted to within the scope of the invention, as claimed, without departing from the spirit thereof.

For a full understanding of the invention and the merits thereof, references is to be had in the following description and the drawing hereto attached, in which:

Figure 1 is a side view of a spindle such as used in a silk quilling machine.

Figure 2 is an enlarged longitudinal, sectional view on the line 2-2 of Figure 1, the intermediate portion of the spindle being broken away and the dotted lines indicating a drift or analogous device in position for removing a journal.

Figure 3 is an end view of the spindle.

Figure 4 is a perspective view of an end portion of a modified form of spindle.

Corresponding and like parts are referred to in the following description and designated in the several views of the drawing by like reference characters.

The numeral 1 denotes the metal body of a spindle, such as generally provided for use in a silk quilling machine. An axial opening 2 is formed in each end of the spindle and receives a journal 3 which is set therein

and is removable therefrom to admit of replacement. The journal 3 is pressed into the opening 2 in a manner to prevent accidental displacement. Longitudinal grooves, or channels 4 are formed in the sides of the spindle 1 for reception of the usual springs, not shown, provided to hold the quill or bobbin upon the spindle.

In accordance with the invention a transverse opening 5 is formed adjacent each end of the spindle and intersects the axial opening 2. A groove or channel 6 is formed in a side of the spindle and extends from the transverse opening 5 through the extremity of the spindle and is in communication with the axial opening 2. The groove or channel 6 may form an extension of one of the grooves 4, as indicated most clearly in Figures 1 and 2 of the drawing, or it may form part of a groove formed in a side of a spindle which otherwise is devoid of grooves or channels, as indicated in the modification shown in Figure 4. The groove 6 provides a passage for a drift 7 or like tool or device, whereby the journal 3 may be removed from the opening 2. The end of the drift 7 is introduced into the opening 5 in the rear of the journal 3, the latter being removed by tapping the drift by means of a hammer, the point of the drift following the journal 80 through the groove or passage 6.

The invention provides for the ready removal of a worn journal and the replacement thereof by a new journal without necessitating loss of the spindle and the replacement thereof in its entirety by a new spindle, which, in the aggregate, entails some considerable expense which is obviated by the arrangement which provides for replacement 90 of the worn journal.

Some types of spindles are devoid of the transverse opening 5. The type of spindle shown is for silk quilling machines and the opening 5, at one end thereof, receives the screw by means of which the usual spool, not shown, is secured thereto. The opening 5 at the opposite end of the spindle receives the wire springs, not shown, which are fitted in the grooves or channels 4.

Having thus described the invention, I
claim:—

1. A spindle provided with an axial opening and an intersecting transverse opening
5 and having a slot formed in a side thereof and extending from the transverse opening through the end of the spindle and communicating with the axial opening, and a removable journal pressed into the axial
10 opening and removable therefrom by means of a drift which has a free passage through the side slot leading outwardly from the axial opening.
2. A spindle for silk quilling machines
15 consisting of a metal body provided in its sides with longitudinal grooves and formed in opposite ends with axial openings and adjacent the ends with intersecting transverse openings, and having one of the side grooves extended through the end of the spindle and in communication with the axial opening, and a replaceable journal pressed into each of the axial openings.

In testimony whereof I affix my signature.
